CRADLE SUPPORT FOR A CAMERA

Harry E. Mazur, P.O. Box 4508,
Palm Springs, Calif. 92262

Filed July 30, 1973, Ser. No. 383,765

Term of patent 14 years

Int. Cl. D16—05

U.S. Cl. D61—1 G

FIG.- 3

FIG.- 4

FIG.- 5

FIG.- 7

FIG.- 6

FIG. 1 is a rear perspective view of a cradle support for a camera showing my new design with the upper portions of the strap having been omitted for convenience of illustration;

FIG. 2 is a front perspective view thereof;

FIG. 3 is a front elevational view thereof with the strap omitted;

FIG. 4 is a rear elevational view of FIG. 3;

FIG. 5 is a top plan view of FIG. 3;

FIG. 6 is a bottom plan view of FIG. 3; and

FIG. 7 is a left side elevational view of FIG. 3.

I claim:

The ornamental design for a cradle support for a camera, as shown.
